CLAIM

The ornamental design for a bottle, as shown and described.

DESCRIPTION

FIG. 1 is a front and left side perspective view from above of a bottle showing our new design;

FIG. 2 is a rear elevational view thereof;

FIG. 3 is a right side elevational view thereof;

FIG. 4 is a front elevational view thereof;

FIG. 5 is a left side elevational view thereof;

FIG. 6 is a top plan view thereof; and

FIG. 7 is a bottom plan view thereof.

The broken line showing of a bottle neck is for illustrative purposes only and forms no part of the claimed design.
